DINING ROOM CHAIR SLIP COVER

Leo Mednick, Philadelphia, Pa.

Application January 28, 1935, Serial No. 3,822

2 Claims. (Cl. 155—182)

This invention relates to slip covers for what is commonly known as "dining room chairs" and has for its object the provision of a new and improved cover for this purpose.

5 Dining room chair covers now on the market consist of independent back rest and seat cover portions. These are objectionable for the following reasons:

(a) It is comparatively difficult for the merchant to handle and display the unit. In handling or upon display the elements of a pair often become separated.

(b) The unit cannot be used with all types of dining room chairs.

15 (c) Each pair is of a certain specific size. The merchant must therefore carry not only a plurality of different patterns but also a great many different sizes of each particular pattern.

It is an object of this invention to produce a 20 dining room chair slip cover which will be free from the defects hereinabove outlined.

It is another object of this invention to produce a 25 slip cover for dining room chairs which will be comparatively simple to manufacture and to use.

In one of its broad aspects my novel cover 30 consists of a back rest portion and a seat portion joined together by a flexible intermediate element.

35 In another of its broad aspects my novel cover consists of a back rest portion and a seat portion joined together by a flexible and extensible intermediate element.

40 My novel concepts may be incorporated in a diversity of structures some of which may include therein some but not all of my novel ideas. For the purpose of illustrating my invention I have shown in the drawing, which is attached hereto and forms a part hereof, one of the many structures into which my concepts may be embodied.

45 In the drawing, Figure 1 is a perspective view of my novel cover mounted upon a "dining room arm chair" as the ensemble appears when viewed from a point in front of the chair with the chair in a normal position upon a floor. Portions of the cover and chair have been broken away for the purpose of greater clearness. The chair shown is of the type where the back slats extend to the chair seat.

50 Figure 2 is a fragmentary section taken along the line 2—2 of Figure 1.

Figure 3 is a perspective view of my novel cover shown in Figure 1 mounted upon a dining room arm chair of the type where the back rest slats terminate a distance above the chair seat

as the same appears when viewed from a point in the rear of the chair with the chair in a tilted position. Portions of the cover have been broken away for the purpose of clearness.

Figure 4 is a fragmentary section taken along 5 the line 4—4 of Figure 3.

Figure 5 is a perspective view of a fragment of a cover consisting of the intermediate or joining member and the portions of the back rest and seat portions contiguous thereto.

10 Referring more particularly to the drawing wherein similar reference letters and reference numerals denote similar parts my cover 1 consists of a back rest portion 2, a seat portion 3, and a joining portion 4 intermediate the said seat and 15 back rest portions.

The back rest portion 2 is pocket like in form with the pocket mouth 5 at its lower end as shown. The front panel 7 of the back rest portion 2 has the apertures 24 formed therein to accommodate the arms A of the chair C. In order to permit the back rest portion 2 to be drawn over the back rest member B of the chair C past the arms A of the said chair that portion of the back rest portion 2 below the point P is split. 25 The front and rear panels 7 and 8 respectively of this split portion 9 of the back rest portion 2 are separably joined together by means of the cooperating male and female elements 11 and 12 respectively of the snap fasteners 10.

30 The seat portion 3 consists of the seat element 13, the skirt element 14, and the chair attaching strap 15. The side portions 17 of the skirt element 14 have the cutouts 19 formed therein which accommodate the uprights U of the arms A of the 35 chair C. The rear element 18 of the skirt 14 is split to form two arms 20 and 20' as shown. The free ends 21 and 21' of the arms 20 and 20' respectively are separably connected by means of the cooperating male and female elements of 40 the snap fasteners 10 carried by the said skirt arms 20 and 20'. The strap 15 is made up of the two rubber elements 22 and 22' separably connected by means of the cooperating hook member 45 25 and the eye member 26 of the fastener 27. The outer ends 23 and 23' of the straps 22 and 22' respectively are attached to the side elements 17 of the skirt 14 and to the edge of the seat element 13 at their point of junction.

50 The intermediate joining portion 4 is a continuation of the seat element 13 and is attached to the lower edge 6 of the front panel 7 of the back rest element 2. The joining portion 4 has positioned therein the cooperating male and fe-

male elements 29 and 30 respectively of the snap fastener 31 as shown.

It is obvious from its structure that the dining room chair cover 1 hereinbefore described can be used with any type of dining room chair. If one desires to use the same on a chair of the type shown in Figure 1 where the slats reach to the chair seat then the intermediate or joining portion 4 will fold up on itself and take the position 10 shown at 32 in Figures 1 and 2. If one desires to use the cover on a chair of the type shown in Figure 3 where the back slats are spaced from the chair seat then the intermediate or joining portion 4 will assume the position shown at 33 15 in Figures 3 and 4. The male and female elements 29 and 30 of the snap fasteners 31 are preferably joined together when the cover is in the operative position upon a chair. Where the chair back is higher than normal the snaps 29 20 and 30 are unfastened and the intermediate portion will extend itself upwardly the distance necessary. The slack, if any, will assume either the position shown in Figure 1 or that shown in Figure 3, depending on the type of chair with 25 which the cover is to be used. This extensibility of the intermediate portion adapts it for use with chairs varying greatly in size.

Although the cover 1 shown in Figures 1 to 5 can be used with plain dining room chairs instead 30 of dining room arm chairs yet I prefer to make the following changes in the cover shown when the same is to be used with plain dining room chairs:

(a) The tubular back rest portion is made continuous by eliminating the apertures 24, the snap fastener elements and sewing together the free edges of the panels 7 and 8 between the points 34 and 35.

(b) The slots or cutouts 19 are eliminated from 40 the skirt sides 17 with the result that the surface of the element 17 is continuous.

The above disclosure is to be understood as being by the way of illustration and not by the way of limitation since many changes may be made in 45 the disclosure herein shown without departing from the spirit of my invention. For this reason it is my desire that the claims which are heretounto appended for the purpose of defining my invention should be limited only by the prior art.

50 Having described my invention what I claim as new and useful is:

1. A slip cover for a dining room chair having a back rest and a seat the lowermost surface of which is spaced from the surface which normally 55 supports the chair, the said cover consisting of a

back rest portion having means formed thereon for detachably attaching said back rest portion to the back of the chair with which said slip cover will be used; a seat portion consisting of a seat cover element, a freely pendant skirt attached along its upper edge to the front and side edges of the said seat cover element and terminating in two free arms each of said arms having attached thereto one of the cooperating elements of a separable fastener, and oppositely disposed straps for detachably attaching the said seat portion to the said chair seat, at least one of the said straps being made of resilient material and each of said straps being attached at one of its ends to the said seat cover and skirt portions and having one of the cooperating elements of a separable fastener attached thereto near the free end thereof; a flexible and extensible portion positioned intermediate and attached to said back rest and seat cover portions; and cooperating elements of a separable fastener carried by said flexible and extensible portion for retaining the folds of said flexible and extensible portion when not in the fully expanded position.

2. A slip cover for a dining room chair having a back rest and a seat the lowermost surface of which is spaced from the surface which normally supports the chair, the said cover consisting of a back rest portion having means formed thereon for detachably attaching said back rest portion to the back of the chair with which said slip cover will be used; a seat portion consisting of a seat cover element, a freely pendant skirt attached along its upper edge to the front and side edges of the said seat cover element and terminating in two free arms each of said arms having attached thereto one of the cooperating elements of a separable fastener, and oppositely disposed straps for detachably attaching the said seat portion to the said chair seat, at least one of the said straps being made of resilient material and each of said straps being attached at one of its ends to the said seat cover and skirt portions and having one of the cooperating elements of a separable fastener attached thereto near the free end thereof; a flexible and extensible portion positioned intermediate and attached to said back rest and seat cover portions; and cooperating elements of a separable fastener carried by said flexible and extensible portion for retaining the folds of said flexible and extensible portion when not in the fully expanded position.

LEO MEDNICK.
